STOVE CONSTRUCTION

Guy C. Davis and Herbert J. Moon, Milwaukee, Wis., assignors to National Enameling & Stamping Co., Inc., Milwaukee, Wis., a corporation of New Jersey

Application October 28, 1937, Serial No. 171,435

6 Claims. (Cl. 126—39)

The present invention relates to stoves, and more in particular to stoves used for domestic purposes.

Among the objects of the present invention is 5 to provide a stove which is simple and inexpensive to make, compact in its construction and easy to operate.

Still another object of the present invention is to provide a novel stove including a movable 10 member provided with a heating compartment, which member, when not in use, serves to provide a flat top stove but which, in its operative position, is adapted to overlie heating means associated with said stove.

15 The present invention contemplates the idea of providing a stove of compact construction which can be conveniently used in modern apartments where space limitations are such that the size and form of the stove must be taken into 20 consideration. A stove made in accordance with the present invention therefore includes as an element in the structure a member provided with a heating compartment, which member is movable from its inoperative position to such a position 25 that the heating compartment overlies heating means of the stove, the member, when in its inoperative position, being formed as a portion of said stove so that the entire assembly is neat in appearance and is compact so as to take the 30 minimum of space.

Still another object of the present invention is to provide a stove including a movable member having a heating compartment, which member, when the heating compartment is in its inoperative 35 position, has a wall forming the top of said stove and which member can be moved into a position so that the heating compartment overlies the heating means of the stove.

The present invention also comprehends the 40 idea of providing a compact stove construction including a movable member having a heating compartment, which member, when in one of a plurality of positions, has a wall forming the top of the stove which is adapted to support articles in heat transfer association with heating means of the stove and which member, when in another position, disposes the heating compartment in overlying relation to said heating means.

Another object within the purview of the present invention is to provide a compact stove of 45 box-like construction having a movable member provided with a heating compartment movable as above indicated and in association with which is a closure member adapted to close the recess in which said member is located in the body of 50

the stove when said member is moved into a position to dispose the heating compartment above the heating means of the stove.

Still a further object of the present invention is to provide novel means for holding the movable member of the stove in a plurality of positions and which means is so constructed and arranged as to facilitate the movement of said member from one position to another. More particularly, the present invention contemplates the use of 10 resilient means which is constructed and arranged so as to have moments of force throughout the movement of the movable member substantially conforming to the moments of force required to move said movable member, said force applied by said resilient means being applied in a direction to assist in the moving of said member from a position in which the heating compartment is in its inoperative position to a position where the said heating compartment 15 is in its operative position.

Other objects, features, capabilities and advantages are comprehended by the invention, as will later appear and as are inherently possessed thereby.

25 Referring to the drawings:

Figure 1 is a view in perspective showing a stove made in accordance with the present invention;

Figure 2 is a view in perspective of the stove disclosing the movable oven member disposed between its inoperative and operative positions;

Figure 3 is a view in perspective of the stove disclosing the appearance of the same when the oven is in a position above the heating means of 30 said stove;

Figure 4 is a view in front elevation of the stove shown in Figure 1 of the drawings disclosing more in detail the mounting for the movable oven member;

Figure 5 is a view in cross-section taken in the plane represented by lines 5—5 of Figure 4 of the drawings and showing the oven in its normally inoperative position below the burners of the stove;

Figure 6 is a view in cross-section taken in a plane corresponding to the plane indicated as 45 5—5 of Figure 4 of the drawings, but showing the oven disposed in overlying relation to the burners of the stove;

Figure 7 is a view in cross-section similar to Figure 5 of the drawings but disclosing resilient means for facilitating the movement of the oven member;

Figure 8 is a view in cross-section similar to 50

Figure 6 of the drawings disclosing the resilient means of Figure 7 and the position thereof when the oven is in its operative position;

Figure 9 is a graph showing the relationship between the moment exerted by the resilient means of Figures 7 and 8 and the turning moment required to move the oven from its inoperative position to its operative position.

Referring now more in detail to the drawings, 10 an embodiment selected to illustrate the present invention comprises a body 2 which is supported upon a base 4, it being understood that the body 2 may be supported upon any desired means and connected thereto in any manner. The body 2 15 comprises a fixed part 6 which has a front side including closure members 8 and 10. These closure members may be hinged whereby access may be gained to inner compartments of the stove, or, if desired, the member 10 may form 20 the front of a drawer adapted to hold cooking utensils and the like. This fixed part 6 of the stove is further provided with a top 12 having a grate or grill 14 which is immediately above a plurality of burners 16, 18 and 20 whereby a 25 plurality of cooking utensils may be supported above the burners for cooking purposes. The stove body 2 further includes the splash-back 22 as is customary in stoves of this type, and also a recess 24 formed in part by the stationary part 30 6 and in part by the side wall 26, within which is disposed a movable part or member 28. This member 28 is of box-like construction having a compartment 30 adjacent one end enclosing a plurality of burners 32 and 34, which compartment 35 is formed in part by an end wall 36 provided with a grill or grating 38 disposed immediately adjacent and above the burners 32 and 34 so that when the movable member 28 is in the 40 position as shown in Figures 1, 4, 5 and 7 of the drawings, the end wall 36 forms a part of the top of the stove and is disposed in substantially the same plane as the wall 12. This end wall 36 and grating 38 therefore provide a support for cooking utensils when it is desired to cook food 45 over the burners 32 and 34, or a support for utensils when cooking is being done over the burners 16, 18 and 20.

This movable member 28 is further provided with an oven or heating compartment 40 which 50 is normally disposed below the plane of the burners 32 and 34. When the member 28 is in the position as shown in Figures 1, 4, 5 and 7 of the drawings, but which oven or heating compartment 40 is adapted to be disposed in overlying relation to the burners 32 and 34 when the oven is moved or rotated into a position as shown in Figures 3, 6 and 8. When the oven or heating compartment is in its lower or inoperative position, the front face 42 of the member 28 is overlapped 55 by the closure member 44 which finishes the front side of the stove so as to make a pleasing appearance but which closure member is opened as shown in Figure 2 when it is desired to move the oven into overlying relation to the burners 32 and 60 34. After the oven has been moved to said position, the closure member 44 is released and the same is disposed in the position as shown in Figure 3 of the drawings to close the lower part of recess 24 and to form a finished construction for 65 the front side of the stove. The oven or heating compartment is provided with the closure member 46 whereby access may be gained thereto for putting in food or other material to be cooked or otherwise treated.

70 75 In connection with the present invention, it

should be noted that the burners 16, 18 and 20, and 75 32 and 34 are of the general type usually found in kerosene stoves, control of the former being effected by way of the closure member 8 and the latter by way of a closure member 47 provided for the compartment 30 when the heating compartment is in its inoperative position and by way of a closure member 48 provided for the compartment 30 when the heating compartment is in its overlying relation to said burners 32 and 34. 10 These burners are diagrammatically shown in the present application and are regulated through the usual mechanism generally represented as 50 on the drawings, the operation of which, of course, is well understood and needs no further description. It is to be noted, however, that although the present embodiments disclose a stove of the kerosene type, nevertheless the invention is not to be limited thereto but is to apply to all stoves irrespective of whether the heating means is 20 adapted for use with kerosene or is of the type generally used for gas or other heating mediums.

In order to rotate the member 28 as indicated, a plurality of roller members 52 and 54 are mounted upon opposite sides of said member, which rollers are disposed to cooperate with the circular tracks 56 and 58 mounted upon the stationary part 6 and the side wall 26, respectively, whereby the member 28 is rotatably supported upon said tracks. Although the rollers and tracks are disclosed as being mounted upon the member 28 and the stove structure, respectively, nevertheless it will be clearly appreciated that such structure may be reversed and the rollers mounted upon the stove structure and the guides or tracks 30 35 mounted upon the movable member 28. The wall of the stationary part 6 within the track 56 is cut out to accommodate the burner mechanism 50 so that such mechanism will not be interfered with in any way whatsoever upon rotation of the 40 member 28 from one position to another. It is also to be noted, as indicated in Figure 7 of the drawings, that the splash-back at 60 is cut away to accommodate member 28 upon a swinging of the oven or heating compartment into operative 45 position and that the closure member 44 and the hinge elements therefor are so disposed as to provide clearance as at 62 for the member 28.

It will be clearly appreciated that the stove construction above described is very compact, requiring a minimum of space, and is particularly adapted for use in small apartments where all the available space must be used. The housewife, when cooking food in receptacles, can make use of the burners 32 and 34 in addition to burners 16, 18 and 20, and even though such former burners are not used, the top of member 28 serves as a table upon which articles may be placed. These burners 32 and 34, however, do provide extra cooking facilities when it is not necessary 60 to use the oven for any purpose. However, should the oven be needed for baking or roasting purposes, closure member 44 can be swung downwardly and the member 28 rotated into the position as shown in Figure 3 of the drawings, at which 65 time the burners 32 and 34 serve the dual function of providing heating means for said oven. After the oven has served in its roasting or baking capacity, the member 28 can be rotated into its former position wherein the end wall 36 again 70 serves as a support, as hereinbefore described. It will of course be appreciated that the stove presents a pleasing appearance when member 28 is in either of its positions, and that when the stove is not being used there are no projecting parts 75

above the general plane of the top, thus adapting the same for use as a table upon which various articles may be placed.

The stove may be provided with foldable covers 5 37 and 39, if desired, which are hinged to the stove body adjacent the splash-back 22 and which may be moved into overlying relation to the top 12 and end wall 38, respectively, to keep dirt and dust from the burners and to provide a continuous table top to place articles thereon when the stove is not in use. Either one or both of these covers may be moved to raised or lowered position depending on the burners which are in use or whether the oven is in its operative or inoperative position.

In order to facilitate the moving or rotating of member 28 into a position so that the oven or heating compartment is disposed above burners 32 and 34, a spring 64 is located on each side of said member, one end 66 of these springs being connected to member 28 as shown in Figures 7 and 8, and the other end 68 of these springs being connected to brackets 10 formed on or connected to the stove body. These springs are of such a construction and so arranged with respect to member 28 and the stove body that the turning moments which they apply to the member 28 because of the tension therein are substantially equal to or conform with the turning moments required to lift the member 28 throughout its movement from one position to another.

By referring to Figure 9 of the drawings, the turning moment required to move the oven is shown in the dotted graph 12, while the turning moment exerted by the springs 64 upon member 28 is represented by the full line graph 74. It will be seen by comparing these two graphs that the turning moment applied by the springs 64 is slightly greater than the turning moment necessary to move the oven, and such condition exists until the oven reaches a point approximately 160 degrees from its initial position. At that time the turning moment of the springs is gradually reduced below the turning moment required to move the oven, but inasmuch as the member 28 has been moved so that the oven is practically in its superimposed or overlying relation with the burners 32 and 34, the lack of assistance from the springs 64 is not a disadvantage because the member 28, when in said position, can be easily handled. By constructing and arranging these springs 64 so as to produce the necessary turning moment for the member 28 substantially throughout its entire movement, it will be seen that the oven can be quickly moved from one position to another without any great effort and that in moving the said member 28 from either of said positions to the other said springs act as a counterbalance to prevent damage to the stove and to eliminate objectionable noises.

While we have herein described and upon the drawings shown illustrative embodiments of the invention, it is to be understood that the invention is not to be limited thereto but may comprehend other constructions, arrangements of parts, details and features without departing from the spirit of the invention.

We claim:

1. A stove comprising adjacently disposed box-like members forming a stove of box-like construction, one of said members being stationary and the other of said members being movable into a plurality of positions, heating means adjacent the top of said stove, and means for movably mounting said second-named member, said

second-named member being provided with a heating compartment normally disposed beneath said heating means when said member is in one of its positions and being movable into overlying relation with said heating means when said member is in another of its positions, said second-named member having means for supporting cooking utensils or the like in heat transfer association with said heating means when said second-named member is in said first-named position. 5

2. In a stove, the combination of a stove body comprising a stationary body portion formed in part by a box-like structure providing a compartment, heating means disposed in association with said compartment, said body portion being further formed in part by a wall spaced laterally from said box-like structure providing a recess, heating means disposed in said recess laterally of said first-named heating means, and a body member disposed in said recess and provided with a heating compartment, and means for movably mounting said body member in said recess whereby by said heating compartment can be moved into overlying relation to said second-named heating means. 15

3. In a stove, the combination of a stationary body, heating means associated with said body, additional heating means disposed adjacent said first-named heating means, a member provided with a heating compartment disposed adjacent said body, and means for movably mounting said member for movement of said heating compartment into a plurality of positions, one of said positions being in overlying relation to said second-named heating means and another of said positions being beneath said second-named heating means. 30 35

4. In a stove, the combination of a stationary body, heating means associated with said body, additional heating means disposed adjacent said first-named heating means, a member provided with a heating compartment disposed adjacent said body, and means for movably mounting said member for movement of said heating compartment into a plurality of positions, one of said positions being in overlying relation to said second-named heating means and another of said positions being beneath said second-named heating means, said member having means for supporting cooking utensils or the like in heat transfer association with said second-named heating means when said heating compartment is in said second-named position. 40 45 50

5. In a stove, the combination of a stationary body, heating means associated with said body, a member provided with a heating compartment disposed adjacent said body, additional heating means disposed in normally stationary position in association with said member, and means for rotatably mounting said member for movement of said heating compartment into a plurality of positions with respect to said second-named heating means, one of said positions being in overlying relation to said second-named heating means and another of said positions being beneath said second-named heating means, said member having means for supporting cooking utensils or the like in heat transfer association with said second-named heating means when said heating compartment is in said second-named position. 55 60 65

6. In a stove, the combination of supporting means, a member of box-like structure having a partition wall forming a heating compartment 70 75

- and a second compartment, track and roller means for mounting said member on said supporting means, heating means extending through one of said tracks and into said second compartment and being provided with heat transfer means disposed in said second compartment, said

member being movable upon said track and roller to dispose said heating compartment in a plurality of positions one of which is in overlying relation to said heat transfer means.

GUY C. DAVIS.

HERBERT J. MOON.
